UNITED STATES PATENT OFFICE.

LEWIS BRANDT, OF OAKMONT, PENNSYLVANIA, ASSIGNOR TO INVINCIBLE MANUFACTURING COMPANY, OF PITTSBURGH, PENNSYLVANIA, A CORPORATION OF PENNSYLVANIA.

WASHING-MACHINE

1,115,892.

Specification of Letters Patent.

Patented Nov. 3, 1914.

Application filed October 28, 1913. Serial No. 787,197.

To all whom it may concern:

Be it known that I, LEWIS BRANDT, a citizen of the United States, residing at Oakmont, in the county of Allegheny and State of Pennsylvania, have invented new and useful Improvements in Washing-Machines, of which the following is a specification:

This invention relates to washing machines, and has for an object to produce a machine wherein is combined a horizontal reciprocatory rotary movement of a receptacle for clothes and water with a peculiar construction of the interior of the receptacle directing the movements of the water and clothes so that the clothes are brought into frictional contact with streams of water traveling in opposite directions, and wherein the clothes are returned upon themselves for rubbing or frictional contact, by the reversal of the direction in which the streams of water travel. This combined operation insures a rapid and thorough cleansing of the clothes since the dirt is removed not only by the rubbing action of the water in the receptacle against the clothes, but also by the simultaneous rubbing of one part of the fabric being washed against other parts of the fabric.

Another object of this invention is to provide a chamber or space at the bottom of the receptacle to collect the sediment in the water and to provide a drain for the removal of the sediment, so that the water may again be used, and the water will not have to be replenished for each batch of clothes or articles to be washed.

These and other objects of this invention will be brought out more particularly in the following detailed description of one embodiment of the invention, the same being illustrated in the accompanying drawings, wherein,

Figure 1 is a side elevation of the washing machine. Fig. 2 is an end elevation of the same, showing the gearing. Fig. 3 is a bottom plan view of the washing machine, the dotted lines indicating the receptacle in one of its positions during operation. Fig. 4 is a transverse sectional view taken through the receptacle on the line 4—4 of Fig. 3, and Fig. 5 is a horizontal sectional view taken on the line 5—5 of Fig. 4 looking toward the bottom of the receptacle.

The washing machine of this invention is made up of a frame, a receptacle or cylin-

der pivoted in the frame, a wringer on the frame, and gearing on the frame for operating the cylinder and the wringer.

Referring to the drawings, the frame comprises uprights 10 and 11 joined by vertically spaced apart longitudinal beams 12 and 13. On the end of the beam 12 near the upright 10 is a reinforcing block 14 of suitable shape and dimensions. Intermediate the ends of the beam is a socket 15 of any suitable type in which is fitted to turn a stud 16 depending from a support 17 for the receptacle or cylinder of the machine. In Fig. 3 of the drawings a support 17 is shown with a cross-piece 18 at each end shaped to the configuration of the bottom of the receptacle 19. The ends of the cross-pieces 18 are flanged at 20 to receive bolts 21 adjustably secured to the flanges by nuts 22. The bolts 21 are hinged at their outer ends upon ears 23 carried by the receptacle 19. Laterally extending from the support 17 is an arm 24 to which the gearing is attached for reciprocating the support.

The gearing or operating mechanism of the machine comprises a member 25 suitably mounted upon the upright 10 and having a pulley 26 receiving a belt 27 passing over a relatively large pulley 28. The pulley 26 is fixed upon the outer end of a shaft 29 journaled to the upright 10 and having a pinion 30 on its inner end meshing with a gear 31, the latter being mounted upon a countershaft 32 journaled at one end in the upright 10 and at its opposite ends in a bracket 33 depending from the beam 12. A bevel gear 34 is loose upon the shaft 32 and is adapted to interlock with a clutch sleeve 35 keyed to the shaft 32, the sleeve 35 being shiftable by a lever 36 extending laterally from the frame as shown to advantage in Fig. 2. The bevel gear 34 meshes with a second bevel gear 37 carried on the lower end of a crank shaft 38 mounted vertically in the beam 12 and having a crank arm 39 upon its upper end to which is pivoted one end of a connecting rod 40, the latter having its opposite end pivoted upon the outer end of the arm 24 of the cylinder support 17. The countershaft 32 is also provided with a bevel gear 41 fixed thereon and meshing with a second bevel gear 42 carried upon the lower end of a vertical shaft 43 journaled in the frame. The upper bevel gear 44 is mounted upon the upper shaft 43 and meshes with a pair of op-

- positely turning bevel gears 45 and 46 loose upon a wringer shaft 47. The wringer shaft 47 is supported in bearings by a bracket 48 inclosing the gears 44, 45 and 46, and mounted upon the upper end of the frame. A clutch sleeve 49 is keyed to the wringer shaft between the gears 45 and 46 and may be interlocked with either one of the gears 45 and 46 by a hand lever 50.
- 10 A wringer 51 of any approved type is mounted on the top of the frame in line with the wringer shaft 47 and is operated thereby.
- The receptacle 19 may be of any approved shape and size, a cylinder being disclosed in the present embodiment. The cylinder 19 has flat end walls, is fitted to the support 17 with its axis in a horizontal plane and has an opening in its upper side closed by a removable cover 52.
- 20 Referring particularly to Figs. 4 and 5, the cylinder 19 is provided in its interior with series of arcuate ribs 53 in its opposite sides terminating at their upper ends short of the opening in the top of the cylinder, and terminating at their lower ends short of the bottom of the cylinder providing a chamber or channel 54 extending longitudinally in the bottom of the cylinder. Fitted between the lower ends of the ribs 53 is a detachable false bottom or partition 55 entirely filling the space between the lower ends of the ribs and having perforations or other openings 56 communicating the interior of the cylinder with the longitudinal chamber.
- 30 A drain cock 57 is positioned in the bottom of the cylinder 19 communicating with the chamber 54 whereby the water and sediment in the chamber 54 may be withdrawn from the receptacle from time to time as desired.
- 40 In the opposite ends of the cylinder 19 are placed vertical deflectors. Each deflector 58 comprises a relatively large rib having oppositely inclined vertical sides converging from the end wall of the cylinder 19 to a straight edge for a purpose hereinafter brought out.
- When in use the motor 25 drives the gearing and effects a turning of the counter-shaft 32. The cover 52 is removed from the receptacle and the batch of clothes or articles to be washed is introduced through the opening in the top of the cylinder. The desired quantity of water is also introduced and the cover 52 is replaced. The lever 36 is now operated to move the clutch sleeve 35 into interlocking engagement with the bevel gear 34, which action couples the crank-shaft 38 to the gearing and effects the turning of the crank shaft. As the crank shaft 60 turns the connecting rod 40 is operated to reciprocate the arm 24 and move the support back and forth in a horizontal plane. This imparts a reciprocating rotary movement to the receptacle and causes the water to pass back and forth in opposite directions in op-
- posite sides of the receptacle. The ribs 53 have preferably oppositely beveled faces and deflect the streams of water inwardly against the clothes in the receptacle thus insuring the contact of the water with the clothes. As the streams of water strike against the opposite ends of the cylinder 19 the water is deflected backwardly and centrally of the cylinder by the deflectors 58, thus insuring the deflecting of the streams of water from the sides into the center of the receptacle. The deflected water in conjunction with the rocking movement of the receptacle in a horizontal plane effects the turning over or doubling of the clothes in the receptacle and the return action of the water from the deflectors effects the rubbing of one portion of the fabric against other portions. During the rocking of the receptacle the streams move in opposite directions at the opposite sides of the receptacle and carry certain portions of the clothes in one direction and other portions of the clothes in the opposite direction giving the rubbing or frictional contact desired for removing the dirt from the clothes. The sediment collected in the water by this action gradually settles down into the bottom of the receptacle 19 and passes through the perforations 56 in the false bottom 55. The false bottom 55 acts as a trap and retains most of the sediment within the chamber 54. The drain cock 57 may be opened to withdraw a small amount of water from the receptacle and the sediment collected in the chamber 54. In this manner most of the sediment is removed from the water, and the water may be used several times with cleansing effect making the machine more efficient and economizing in the consumption of time.
- When it is desired to operate the wringer 51 the hand lever 50 is swung to the right or to the left in order to interlock either the gear 45 or 46 to the wringer shaft 47 so as to turn the rollers of the wringer in the direction desired.
- It is, of course, understood that the above specifically described apparatus is but one embodiment of this invention, and that the details of construction may be changed or other devices substituted, the scope of the invention being limited only by the following claims.
- What is claimed is,—
1. In a washing machine, a frame, an elongated receptacle pivoted in the frame for horizontal oscillating movement, operating means on the frame connected to the receptacle for imparting the oscillating movement thereto, and means within the receptacle for directing the water in lateral streams longitudinally in the receptacle, and for deflecting the water centrally in the receptacle from the ends thereof.
  2. In a washing machine, a frame, a socket

in the lower end of the frame, a support having a depending stud engaging in the socket to pivotally connect the support to the frame, a receptacle detachably mounted on said support, operating means on the frame engaging said support to oscillate the same in a horizontal plane, and means within the receptacle for deflecting streams of water centrally of the receptacle when the latter is oscillated.

3. In a washing machine, a receptacle, means for oscillating the receptacle in a horizontal plane and direct water in the receptacle back and forth laterally within the receptacle, deflecting ribs mounted in the sides of the receptacle for directing the streams of water centrally within the receptacle, and deflectors mounted in the opposite ends of the receptacle adapted to deflect the streams of water at the ends of the receptacle toward the central portion of the receptacle.

4. In a washing machine, a frame, an

elongated receptacle pivoted horizontally in the frame, operating means engaging the receptacle to oscillate the same horizontally whereby to produce oppositely flowing streams of the water in the receptacle in the opposite sides thereof, vertical ribs in the sides of the receptacle for deflecting the streams of water inwardly, a perforated false bottom in the lower part of the receptacle between the lower ends of the ribs adapted to collect sediment in the water beneath the false bottom, and a drain cock for drawing off the sediment from beneath the false bottom without emptying the receptacle.

In testimony whereof I have hereunto set my hand in presence of two subscribing witnesses.

LEWIS BRANDT.
